UNITED STATES PATENT OFFICE.

JOSEPH WHITE, OF MIDDLESEX, NEW JERSEY; MINNIE E. WHITE, ADMINISTRATRIX OF SAID JOSEPH WHITE, DECEASED, ASSIGNOR, BY MESNE ASSIGNMENTS, TO R. HOE AND CO., OF NEW YORK, N. Y., A CORPORATION OF NEW YORK.

SHEET DETECTOR.

Application filed October 11, 1919. Serial No. 330,023.

To all whom it may concern:

Be it known that I, JOSEPH WHITE, a citizen of the United States, residing at Middlesex, in the State of New Jersey, have 5 invented a new and useful Improvement in Sheet Detectors, of which the following is a specification.

This invention relates to devices for controlling an operating mechanism in accordance with the position of a sheet and particularly the control of some operating part of a printing press or the like, such as a cylinder trip, a belt shifter or the like, according to the presence or absence of a 15 sheet fed to the feeding point of such a machine. Heretofore such devices have involved constructions, particularly when based on the displacement of a mechanical part, which gave some resistance to the 20 sheet as it was being moved into predetermined position, and which would not render the machine inoperative in the event that the sheet was moved beyond its predetermined position. Some of the objects of my 25 invention are to obviate these defects.

Another object of my invention is to provide a sheet detector on a movable part, such as a sheet-taking cylinder, so arranged that the moving parts may be connected up 30 to the stationary parts of the machine whereby the moving detector may control another portion of the machine.

With these and other objects in view, my invention consists of certain novel features of construction, combination and arrangement of parts as will be more fully described and pointed out in the appended claims.

In the drawings, Figure 1 is a portion 40 of a printing cylinder of a printing press which I have chosen for the purposes of illustration, many of the parts and the operation of this particular cylinder being of the character that is shown in my prior 45 Patent No. 1,178,563, granted April 11, 1916, in which the sheet is fed to the lower portion of the cylinder after having first been gaged by having its edge presented to either stationary or movable gages. Fig. 50 2 is a side elevation of the mechanism shown in Figure 1. Fig. 3 is a view similar to Fig. 2, but taken at the opposite end of the cylinder to show the gripper operating mechanism.

The corresponding parts are referred to both in the specification and in the drawings by similar reference characters.

In the illustrative form of my invention the cylinder 10 is provided with a shaft 11 carrying sheet grippers 12, the ends 13 of the grippers 12 cooperating with a fixed abutment 14 carried by the cylinder on the beam 15 fastened thereto. The gripping point 13 of the gripper 12 and one of the abutments 14 obviously constitute a pair of grippers to engage the sheet S, as shown in Figure 1. A tumbler 16 of the usual type is attached to the shaft 11, and tumbler pins, such as 161, of the ordinary type, may be provided so that the shaft 11 is partially rotated in opposite directions to take and release a sheet, all in the well-known manner. The shaft 11 would be held either with the grippers in closed position, as shown in Fig. 1, or in open position by the usual spring and spring rod illustrated in Figs. 1 and 3, this arrangement also being a device commonly used in the art.

Supported in a poppet 17 in the beam 15 is a support 18 carrying a stud 19 on which is pivoted a three-armed lever, one of which arms 20 is a detent, another of which arms 21 is a weight lever carrying an adjustable weight 22, and the third arm 23 is a detector arm carrying a detector blade 24 adjustably mounted thereon, the adjustment being provided by the screw 25. There may be as many of these three-armed levers spaced across the press as desired, but usually there will be two of them.

Mounted in bearings in the cylinder 10 is a shaft 30 to which is attached a cam lever 31 carrying a cam roller 32 which runs on a cam 33 attached to the side frame of the machine, the roller 32 being held against the cam 33 by a spring 34.

Also attached to the shaft 30 is a switch arm 35 carrying a contact pad 36 adapted to slide over a pair of contact bars 37, 38. As shown in Figure 2, in the form illustrated, the switch bars 37, 38 are on the inside of the outer ring of the cylinder 10. On the outer side of the cylinder 10 are a pair of contact bars 39, 40 to which the bars 37, 38 are connected electrically through the conductors 41, 411. On the side frame of the machine are mounted a pair of contact members 42, 43 connected

respectively to an electric circuit for a purpose to be referred to hereinafter, each of the contact members 42, 43 being spring-seated and each arranged to wipe over one of the contact bars 39, 40 as the cylinder 10 rotates.

On and fastened to the shaft 30 is a two-armed lever positioned opposite the detent 20, one of the arms 45 of this lever being arranged to cooperate with the top of the detent lever 20 and the other arm 46 being arranged to cooperate with the end of the detent lever 20 in a manner to be hereinafter described.

In the illustrative form of my invention a sheet is fed to the cylinder 10 as it is rotating in the direction of the arrow shown in Figure 1, and the sheet is gaged before the grippers 12 close thereon by virtue of the tumbler 16 running off the tumbler pins 161. If, however, no sheet has been presented or has not been properly positioned against the gages either on both sides or on one side of the machine, so that all or a portion of its front edge has not reached the predetermined line to which the sheet should be presented, or in the event that that portion of the sheet which was against the gages was properly positioned but that, due to buckles or wrinkles in the sheet, some portion of it between the gages has passed beyond the predetermined line as the grippers 12 close on it, it is desirable to either stop the machine or trip the cylinders or in some other way render a portion of the machine inoperative so that the improperly positioned sheet will not be spoiled or the printing surface printed upon. The usual method is to trip the cylinders.

While the sheet was being presented and gripped between the gripping points 13 and the abutments 14, the detector blade 24 would be held to the left of the position shown in Figure 1 by the contact between the arm 45 and the detent arm 20, because at this time the roller 32 is running on the high part of cam 33, that is, the part having the smallest radius. After the grippers 12 have closed on the sheet, the roller 32 begins to pass down to the low part of the cam 33, and when it has reached the position shown in Figure 1 the blade 24 has been permitted to turn under the influence of the weight 22 to a position which is the correct position at which the sheet should be positioned. Further rotation of the cylinder will permit the shaft 30 to turn still further under the influence of the spring 34 and the extent of this turning will be determined by the position of the end of the detent 20 in relation to the notches 461, 462 and 463 in the arm 46 of the two-armed lever. For instance, in the position of the sheet shown in Figure 1 the end of the detent 20 is located so that it will enter the deep notch or slot 462 to per-

mit the shaft 30 to have its maximum rotative movement, the presence of the sheet S at the predetermined point holding the blade 24, and therefore the detent 20, in the position shown in Figure 1.

Because of the extent of rotation of the shaft 30 the contact pad 36 is moved to the right of Figure 1 out of contact with the bar 37, so that when the pins 42, 43 contact with the bars 39, 40 in the further rotation of the cylinder, no electrical circuit between them can be established because of the break due to the position of the switch arm 35.

On the other hand, if a sheet S has either not been presented to the gages at all or has not reached them, the weight 22 will swing the blade 24 to the right of the position shown in Figure 1 and will thus elevate the end of the arm 20 so that it will contact with the notch 463, as the shaft 30 is turned, and will thus prevent the spring 34 from rotating the shaft to move the switch arm 35 substantially from the position shown in Figure 1, so that when contact is established between the pins 42, 43 and the bars 39 and 40, an electric circuit can be established between the pins.

Similarly, if a portion of the sheet opposite the blade 24 has for any reason been crowded past the predetermined position, the weight 22 will be restrained so that the detent 20 will be positioned opposite the notch 461 and this likewise will prevent the motion of the pad 36 off the bar 37.

The pins 42, 43 may be connected to any desired electrical apparatus to operate any part of the press, such as a belt shifter or a trip. If a trip is to be operated, then it will be arranged in a well-known manner so that when a current passes through the circuit of which the pins 42, 43 are a part, the cylinders will be moved apart and brought together again when such circuit is broken at a predetermined point in the rotation of the cylinders. Such an electrically operating tripping device directly applicable to machines of the type with which the feed cylinder of my present invention may be used is shown in my prior Patent No. 1,341,693, granted July 1, 1920, in which the usual eccentric for separating one of the pair of cylinders is controlled by a solenoid in an electric circuit, of which a switch controlled by the sheet forms a part. It will be obvious that the wires connected to the pins 42 and 43 in Fig. 1 herein could be led directly to such a solenoid to control the tripping mechanism.

While I have shown my detector as controlling an electric circuit, it will also be understood that it may be used to control mechanical parts in ways which are well understood in the art.

It will be observed that the blade 24 does not contact with the sheet until after it has

been positioned and, in the form illustrated until after the grippers have closed thereon. Consequently, there is no tendency for the contact of the blade 24 with the sheet to 5 prevent the proper positioning of the sheet.

While I have shown and described my invention particularly in connection with a printing press, it will be understood that it may be used in connection with any mechanism for operating on sheets, such as sheet 10 folders or the like.

In the appended claims, the term "edge" is used in its ordinary meaning as defining the boundary of the sheet and not any portion 15 of the sheet inside the boundary thereof.

I claim:

1. A sheet-taking device adapted to engage the head of a sheet, a sheet detector 20 adapted to move into detecting position against the edge of the sheet after the sheet is engaged by said device, and operating mechanism controlled by said detector.

2. A sheet-taking device adapted to engage the head of a sheet, a sheet detector 25 adapted to move toward the edge of the sheet and in a direction generally parallel to the surface of the sheet after the sheet is engaged by said device, and operating mechanism controlled by said detector and 30 made inoperative only when the sheet is in a predetermined position in said device.

3. A cylinder having sheet grippers thereon, means to close said grippers, a movable 35 member, mechanism to move said member and in a direction generally parallel to the surface of the sheet toward the gripping point of said grippers after they are closed and operating mechanism whose operation 40 is controlled by the position of said movable member as determined by the presence or absence of a sheet in said grippers.

4. A cylinder having sheet grippers thereon, means to close said grippers, a movable 45 member, mechanism to move said member and in a direction generally parallel to the surface of the sheet toward the gripping point of said grippers after they are closed and operating mechanism whose operation 50 is controlled by the position of said movable member as determined by the position of a sheet in said grippers.

5. A cylinder having sheet grippers thereon, means to close said grippers, a movable 55 member on said cylinder, mechanism to move said member and in a direction generally parallel to the surface of the sheet toward the gripping point of said grippers after they are closed and operating mechanism whose operation is controlled by the 60 position of said movable member as determined by the presence or absence of a sheet in said grippers.

6. A cylinder having sheet grippers thereon, means to close said grippers, a movable 65

member, mechanism to move said member and in a direction generally parallel to the surface of the sheet toward the gripping point of said grippers after they are closed and operating mechanism adapted to be 70 rendered operative if said member fails to reach or passes a predetermined position and to be rendered inoperative if said member stops at such predetermined position.

7. A cylinder having sheet grippers thereon, means to close said grippers, a movable member, mechanism to move said member and in a direction generally parallel to the surface of the sheet toward the gripping point of said grippers after they are closed, 75 an operating member, means to move said operating member over a predetermined path after said grippers are closed, connections between said movable member and said operating member constructed and arranged 80 to permit said operating member to move over its predetermined path when said movable member is stopped at a predetermined position and to restrain such movement when said movable member fails to reach or 85 passes said predetermined position, and mechanism controlled by the final position of said operating member.

8. A cylinder having sheet grippers thereon, means to close said grippers, a movable 90 member, mechanism to move said member and in a direction generally parallel to the surface of the sheet toward the gripping point of said grippers after they are closed, an operating member, means to move said operating member over a predetermined path after said grippers are closed, connections between said movable member and said operating member constructed and arranged 95 to permit said operating member to move over its predetermined path when said movable member is stopped at a predetermined position and to restrain such movement when said movable member fails to reach or 100 passes said predetermined position, and mechanism controlled by the final position 105 of said operating member.

9. A cylinder having sheet grippers thereon, means to close said grippers, a movable member adapted to be moved yieldingly and in a direction generally parallel to the surface of the sheet toward the gripping point of said grippers, means to prevent said movable member from moving until after said grippers are closed, an operating member, means to move said operating member yieldingly, connections between said movable member and said operating member adapted to limit the motion of said movable member when said movable member moves past or fails to reach a predetermined position, and mechanism controlled by the final position 110 120 125 130 of said operating member.

10. A cylinder having sheet grippers thereon, means to close said grippers, a pivoted detector blade on said cylinder adjacent the gripping point of said grippers, means to hold said blade in advance of said gripping point before said grippers close, means to move said blade yieldingly toward said gripping point after said grippers are closed, a movable operating member on said cylinder, mechanism to move said operating member yieldingly after said grippers are closed, a detent connected to said blade and adapted to engage said operating member if said blade moves past or fails to reach a predetermined position, and mechanism controlled by the position of said operating member.

11. A cylinder having sheet grippers thereon, means to close said grippers, a pivoted detector blade on said cylinder adjacent the gripping point of said grippers, means to hold said blade in advance of said gripping point before said grippers close, means to move said blade yieldingly toward said gripping point after said grippers are closed, a pivoted operating member on said cylinder, mechanism to move said operating member yieldingly after said grippers are closed, a detent connected to said blade and swinging therewith, said operating member being provided with notches with which said detent is adapted to engage, when said blade passes or fails to reach a predetermined position, to limit the motion of said operating member, and mechanism controlled by said operating member.

12. A rotating cylinder having sheet grippers thereon, stationary supports for said cylinder, a sheet detector on said cylinder

and controlled by the position of a sheet presented to said grippers, an operating lever, means to move said operating lever yieldingly, connections between said detector and said operating lever to control the movement of said operating lever in accordance with the position of said detector, a switch on said cylinder connected to said operating lever, and means to establish an electric circuit between said cylinder and its support and through said switch.

13. A rotating cylinder having sheet grippers thereon, stationary supports for said cylinder, a sheet detector on said cylinder and controlled by the position of a sheet presented to said grippers, an operating lever, means to move said operating lever yieldingly, connections between said detector and said operating lever to control the movement of said operating lever in accordance with the position of said detector, a switch on said cylinder connected to said operating lever, a pair of contact bars adapted to be connected electrically through said switch and a pair of contacts in said stationary supports and each adapted to contact with one of said bars as said cylinder rotates.

14. A sheet-taking device, a sheet detector comprising a member adapted to contact with the edge of a sheet, means to hold said member in advance of the edge of a sheet being presented to said sheet-taking device until the sheet is in position to be taken by said device and to permit it to be moved toward the edge of the sheet after the latter is so positioned, and operating mechanism controlled by said member.

JOSEPH WHITE.
